LOCK PARTS AND METHOD OF FORMING
THEMAndrew L. Schuyler, La Grange, Ill., assignor to
Western Electric Company, Incorporated, New
York, N. Y., a corporation of New York

Application June 14, 1935, Serial No. 26,599

8 Claims. (Cl. 29—148)

This invention relates to lock parts and a method of forming them, and more particularly to bolts for rotor center tumbler type locks and a method of forming them.

5 An object of the present invention is to provide a simple and inexpensive lock bolt and an economical method of manufacturing it.

In accordance with one embodiment, the invention, as applied to locks for telephone pay station equipment, contemplates a lock bolt for a rotor center tumbler type lock formed from sheet metal stock by blanking, perforating and bending the lower half of the bolt and attaching a flat plate thereto at the latch portion, then reducing 10 the thickness of the latch portion of the bolt by swaging it to the proper thickness and riveting a substantially U-shaped upper half of a lock bolt, which has been formed by a series of punching, shaving, bending and slotting operations on 15 a punch press, to the lower half of the lock bolt assembly.

In accordance with another embodiment, the upper half of a lock bolt assembly is formed by perforating and stamping a blank from a sheet 20 of flat metal stock, simultaneously shearing and bending a portion of the blank, forming a second bend in the blank and attaching the part just described to a blank of a predetermined shape by welding it thereto, then swaging the joined parts 25 to a predetermined dimension in thickness and shaving the edges of the joined parts to a predetermined contour.

Other features and advantages of the invention will become apparent from the following detailed description when considered in conjunction 30 with the accompanying drawings, wherein

Figs. 1 to 4 are plan views of the lower portion of the lock bolt assembly in the various stages of its manufacture;

40 Figs. 5 and 6 are end views of the upper half of the lock bolt assembly as shown in Figs. 2 and 3;

Figs. 7, 8, 9 and 10 are a plan view, a side view, 45 a plan view and an end elevational view, respectively, of the upper half of the lock bolt assembly in the various stages of its manufacture;

Figs. 11 and 12 are plan views of the upper and 50 lower half of the lock bolt assembly after they have been assembled illustrating the two stages of manufacture through which they pass after they are assembled;

55 Fig. 13 is an end view of the structure shown in Fig. 12;

Figs. 14, 15, 16, and 17 are plan views of another type of upper half of a lock bolt assembly;

Fig. 18 is a plan view of the lower half of a lock bolt assembly with which the upper half shown in Figs. 14 to 17, inclusive, is used;

Figs. 19, 20 and 21 are plan views of the assembled upper and lower parts of the lock bolt assembly during the various steps in its manufacture, and

Fig. 22 is a plan view of a lock with the cover 10 plate removed and illustrating the type of lock bolt assembly shown in Figs. 19 to 21, in position in a lock.

In the embodiment of the invention disclosed in Figs. 1 to 13, a lock bolt assembly is formed by stamping a blank 1 (Fig. 1) from a strip of sheet metal stock wherein the blank 1 has a slot 2 and apertures 3 and 4 formed therein in the stamping operation. A projecting portion 5 is also formed as a part of the blank 1 in this stamping operation.

The blank 1 is then subjected to another punching operation in which operation the projecting portion 5 is bent upwardly as shown in Fig. 2 to provide a strengthening rib when the bolt is assembled in a lock.

In the next succeeding operation, a flat metal strip 6 is secured to the lower or forward end of the blank 1 by welding it at points 7 as shown in Fig. 3. This is to provide a latching portion 30 on the bolt of a predetermined thickness.

After the strip 6 is secured to the blank 1 as shown in Fig. 3, the lower or forward end of the bolt is subjected to pressure to swage that portion thereof to the desired thickness. This will result in forcing some of the metal of the blank 1 and the strip 6 out of its former shape as indicated by the rough edges at 8 (Fig. 4). The assembled strip 6 and blank 1 are then ready to be assembled with the upper half of the bolt 40 assembly.

The upper half of the bolt assembly is formed by stamping a blank 9 having the contour shown in Fig. 7 from sheet metal stock. This blank 9 is then stood on edge and shaved to form a beveled edge at 10 and a V-shaped groove at 11 (Fig. 8). After having the beveled edge and V-shaped groove formed in the blank 9, the blank is again laid flat and slotted in a punch press as shown at 12 (Fig. 9). After this slotting operation, the blank 9 is subjected to another punch press operation which forms it to a substantially U-shaped contour as shown in Fig. 10 wherein the sides are formed. These sides will, in the finished lock shown in Fig. 22, cooperate with 50 55

the code notches 44 formed in the tumblers upon operation of the lock.

It will be noted that in Figs. 7, 9 and 10 the blank 8 has a pair of upwardly extending lugs 13. These lugs are inserted in the apertures 3 and 4 in the blank 1 and serve as rivets to hold the formed blank 8 which constitutes the upper half of the bolt assembly in place on the lower half of the bolt assembly.

10 After the parts are thus assembled as shown in Fig. 11, the edges of the latching portion of the bolt which is made up of strip 6 and forward or lower end of the blank 1 are shaved at 15 to the desired contour, thereby removing the rough edges shown at 8 (Figs. 4 and 11). The final bolt assembly comprising the upper half formed from the blank 8 and the lower half formed from the blank 1 and strip 6 will then be as shown in Figs. 12 and 13. In this condition the bolt assembly is ready to be assembled as shown in Fig. 22 in a lock of the same general type but not the exact construction of the lock shown in the patent to O. A. Shann, 1,793,254, patented February 17, 1931.

25 In another embodiment of the invention a similar type of lock bolt assembly is provided. This latter type of lock bolt is formed in a manner similar to that described hereinbefore except that being somewhat simpler in construction 30 there are fewer operations required in the manufacture of it. Figs. 14 to 21 illustrate the steps in the manufacture of this type of lock bolt.

In accordance with this embodiment of the invention, a blank 20 is stamped in one operation from sheet metal stock and perforated to the contour shown in Fig. 14 wherein the blank stamped from the stock has an aperture 21 therein. This blank will ultimately constitute the upper half of the lock bolt assembly, and a part 40 of the latching portion and lug of the bolt. After the blank 20 has been stamped from stock it is sheared along the line 22 and bent along the line 23 as shown in Fig. 15. After the blank has been stamped as shown in Fig. 14 and bent as shown in Fig. 15, it is again subjected to a bending operation to bend a portion of it forwardly as shown in Fig. 16 along the line 24. After the bending operations have been performed, the blank is set 50 flat in a fixture and shaved to form a V-shaped groove as shown at 25 (Fig. 17) in the portion thereof which was bent downwardly at 23 as shown in Fig. 20 and then twisted forwardly by bending along the line 24 as shown in Fig. 16. The blank 20 which has been formed to the shape 55 shown in Fig. 17, constitutes the upper half of this type of lock bolt assembly and also provides a thickening or filler plate for the latching portion of the bolt.

The lower portion of the bolt is formed by 60 stamping a blank 26 from sheet metal stock to the contour shown in Fig. 18, wherein there is a guide slot 40 and a rounded cut out portion 41 for cooperation with an actuating lever on the barrel 32 of a lock (Fig. 22). The blank 26, 65 as shown in Fig. 17, is secured to the blank 20 by spot welding it thereto at the points 27 whereupon the assembled upper and lower halves of the assembly are subjected to pressure at the latching portion. This operation will reduce the 70 thickness of the latching portion by swaging the surplus metal downwardly and to the sides as shown in Fig. 20 to reduce the thickness of the latching portion to the desired dimension (see Fig. 20). After the upper and lower halves of 75 the assembly have been joined together as de-

scribed and the latching portion has been swaged to the desired thickness, the edges of the material swaged out of their former position in the swaging operation are shaved along the lines 30 to the desired contour and the lock bolt assembly 5 is ready to be assembled in a lock of the type disclosed in Fig. 22 and Patent No. 1,793,254, wherein the lock bolt assembly designated generally in Fig. 22 by the numeral 31 is assembled with a lock center or barrel 32, movable tumblers 33, and fixed tumbler 34 in a housing 35. The lock shown in Fig. 22 with the top plate removed is a known type of rotor center tumbler type lock as shown by Patent No. 1,793,254 in which the lock bolt assembly 31 acts in the same 15 manner as heretofore and is of the same general contour as those heretofore used, the distinction being that the bolt is formed entirely by punch press operations from sheet metal stock and is therefore much cheaper to manufacture 20 than those heretofore known.

What is claimed is:

1. In a lock, a bolt assembly comprising a latch portion formed of two sheet metal strips welded together and swaged to the desired thickness, a 25 base portion comprising a prolongation of one of said sheet metal strips formed to slide in the lock and to cooperate with an actuating lever in the lock, and an upper portion formed of a single piece of sheet metal bent to form a lug or stud 30 for cooperation with the tumblers of the lock.

2. A method of forming bolts for rotor center tumbler type locks which includes punching a blank from sheet metal stock to a predetermined configuration to form a part of a latch 35 portion, a lever cooperating portion and a guide portion, punching a blank from sheet metal stock for use as an upper bolt portion, bending the second mentioned blank to a shape so that a portion thereof will cooperate with the tumblers of a lock, and securing it to said first blank.

3. A method of forming bolts for rotor center tumbler type locks which includes punching a blank from sheet metal stock to a predetermined 45 configuration to form a part of a latch portion, a lever cooperating portion and a guide portion, punching a blank from sheet metal stock for use as an upper bolt portion, bending the second mentioned blank to a shape so that a portion thereof 50 will cooperate with code notches in the tumblers of a lock, shaving a V-shaped safety notch in a portion of said bent blank, welding a thickening plate to the first formed blank, swaging the joined first mentioned blank and thickening plate to the 55 desired thickness to form a latch portion, and shaving the latch portion to the desired contour.

4. A method of forming bolts for rotor center tumbler type locks which includes punching a blank from sheet metal stock to a predetermined 60 configuration to form a part of a latch portion, a lever cooperating portion and a guide portion, punching a blank from sheet metal stock for use as an upper bolt portion, bending the second mentioned blank to a shape so that a portion 65 thereof will cooperate with code notches in the tumblers of a lock, shaving a V-shaped safety notch in a portion of said bent blank, welding a thickening plate which may constitute part of the bent blank to the first formed blank, swaging the joined first mentioned blank and thickening plate to the 70 desired thickness to form a latch portion, and shaving the latch portion to the desired contour.

5. In a lock, a bolt assembly comprising a latch 75

portion formed of two sheet metal strips welded together and swaged to the desired thickness, a base portion comprising a prolongation of one of said sheet metal strips formed to slide in the lock and to cooperate with an actuating lever in the lock, and an upper portion formed of a single piece of sheet metal bent to form a lug or stud for cooperation with the tumblers and having a V-shaped groove shaved therein for cooperation 10 with corresponding safety grooves in the tumblers of the lock.

6. In a lock, a bolt comprising a base plate formed from a single sheet of metal and having a guide slot formed therein, a portion adapted to cooperate with the actuating lever of the lock and an extending portion to provide a part of the latching portion of the lock, a thickening plate attached to the base at the latching portion thereof, said thickening plate and base being swaged 20 to the desired thickness and shaved to the desired contour, an upper portion adapted to cooperate with the tumblers of the lock comprising a sheet metal blank punched to a predetermined contour and having its edges shaved to form a bevel on 25 one edge and a V-shaped groove in the other edge, the upper portion being bent to cooperate with the safety notches and code notches on the tumblers of the lock and being fixed to the base plate by riveting.

7. A method of forming bolts for rotor center tumbler type locks comprising punching a blank from sheet metal and concurrently perforating an aperture therein, shearing and bending a portion of the blank down to the aperture to

bend a portion of the blank at right angles to the remainder of the blank, forming a right angle bend in the blank at right angles to the bend previously formed therein, shaving a V-shaped notch in one of the bent portions, punching a base 5 from sheet metal stock, welding a portion of the first mentioned blank to the base, swaging the base and first mentioned blank where they are joined together by welding to a predetermined thickness, and shaving the welded together base 10 and blank to the desired contour for use as the latching portion of a lock bolt.

8. A method of forming bolts for rotor center tumbler type locks comprising punching an apertured and slotted blank from sheet metal stock, 15 bending a projecting portion of the blank at right angles to the remainder thereof to form a strengthening rib, welding a flat sheet metal plate to a projecting portion of the blank, swaging the welded together portions of the blank and the 20 plate to a predetermined thickness, forming an upper portion of the bolt by punching an irregularly shaped blank from sheet metal stock, standing the irregularly shaped blank on edge, and shaving a bevel on one edge thereof and a V- 25 shaped groove on the other edge thereof, punching a notch in the blank thus formed, bending the blank to a substantially U-shaped configuration, inserting two portions of the irregularly shaped blank which is now of U-shaped configuration 30 in the apertures formed in the base, riveting the U-shaped member to the base, and shaving the latching portion to the desired contour.

ANDREW L. SCHUYLER.
